UNITED STATES PATENT OFFICE.

JAMES F. CALLAHAN, OF KNOXVILLE, TENNESSEE.

MILLSTONE-DRIVER.

SPECIFICATION forming part of Letters Patent No. 271,572, dated January 30, 1883.

Application filed June 14, 1882. (No model.)

To all whom it may concern:

Be it known that I, JAMES F. CALLAHAN, of Knoxville, in the county of Knox and State of Tennessee, have invented a new Improved 5 Millstone-Driver, of which the following is a full, clear, and exact description.

The object of my invention is to insure a steady and uniform rotation of the millstone and prevent irregularities in the movements 10 of the motor from affecting the movements of the millstone; and to this end the invention consists in the peculiar construction and arrangement of parts, as hereinafter fully described, and pointed out in the claims.

15 Reference is to be had to the accompanying drawings, forming a part of this specification, in which similar letters of reference indicate corresponding parts in all the figures.

Figure 1 is a cross-sectional elevation of a 20 millstone combined with my improved driver. Fig. 2 is a plan view of the under side of the upper removable cap and arms of my improved millstone-driver. Fig. 3 is a plan view of the collar or annular flange on the spindle for supporting the removable cap and arm.

The vertical spindle A is provided with a collar or annular flange, B, provided on its upper side with two opposite vertical projections, C, having radial ends, the length of each projection C being somewhat less than a quarter-circle, as shown in Fig. 3. Rubber cushion-blocks D D' are placed on the top of the collar B and against the radial or beveled ends of the projections C. In place of the rubber blocks D D', any other suitable cushions or springs may be used. The cushions D are preferably made larger than the cushions D', and the larger cushions, D, are placed opposite to each other, as are also the smaller cushions, D'. 30 A cap, E, provided in its top with an aperture, F, through which the upper part of the spindle A' A can pass, is adapted to rest on the collar or flange B and to inclose the blocks or projections C on the collar B. This cap E is provided with two arms, G, projecting in opposite directions, the inner ends, H, of these arms being beveled and projecting into the cap E from the sides of the same, so that when the cap E rests on the collar B the beveled ends 35 H of the arms G will be between the cushion-blocks D D', as indicated in dotted lines in Fig. 3. Rubber blocks J or cushions or springs

are contained in recesses in the ends of the upper surfaces of the arms G, these cushions J being provided to prevent the millstone K from 55 injuring or breaking these arms G when the stone rocks, and to prevent undue rocking of the stone. The millstone K is supported from the top of the spindle by means of the balance-rynd L in the usual manner. The arms G pass 60 into recesses M in the stone K, which recesses are adapted to receive these arms.

The operation is as follows: If the spindle A is rotated in the direction of the arrow a', the cushions D will press against the sides of 65 the beveled or wedge-shaped ends H of the arms G, and the box or cap E will be rotated in the direction of the arrow a'. The arms G press against the sides of the recesses M on the stone K, and thus rotate the stone in the direction of the arrow a'. The stone is not connected directly with the spindle, and all the irregularities of the movement of the spindle are taken up by the cushions or springs D, and thus prevent irregular or unsteady movements 70 of the stone. The back lash or reaction of the stone is taken up by the smaller cushions or springs, D'. If the stone is rocked by the rapid movement of the spindle, the tops of the recesses M strike on the cushions J on the 75 arms G, and thus limit the rocking movement of the stone.

Having thus described my invention, I claim as new and desire to secure by Letters Patent—

1. In a millstone-driver, the combination, 85 with the spindle A, provided with a collar or annular flange, B, having projections C, with radial or beveled ends, of the springs or cushions D D', and the cap or box E, provided with opposite arms G, having inner beveled ends, H, 90 substantially as herein shown and described, and for the purpose set forth.

2. In a millstone-driver, the combination, with the spindle A, provided with a collar or annular flange, B, of the springs or cushions 95 D D', and the box or cap E, provided with opposite arms G, having inner beveled ends, H, and of the springs or cushions J J on these arms, substantially as herein shown and described, and for the purpose set forth.

JAMES F. CALLAHAN.
